FITTING FOR JOINING TUBULAR MEMBERS

Peter R. Hollaender, Cincinnati, Ohio, assignor to The Hollaender Manufacturing Co., Cincinnati, Ohio, a corporation of Ohio

Application June 16, 1958, Serial No. 51,366

Term of patent 14 years

(Cl. D54—1)

Figure 1 is a side elevational view of a fitting for joining tubular members showing my new design.

Figure 2 is an end elevational view thereof.

Figure 3 is a top plan view thereof.

Figure 4 is a bottom plan view thereof.

I claim:

The ornamental design for a fitting for joining tubular members, substantially as shown.
